J. T. MURPHY

BEATING ENGINE

Filed Oct. 23, 1922

Inventor
James T. Murphy
William Broadway
McCall & Pease Atty.

UNITED STATES PATENT OFFICE.

JAMES T. MURPHY, OF CHICAGO, ILLINOIS.

BEATING ENGINE.

Application filed October 23, 1922. Serial No. 596,272.

My invention relates to improvements in beating engines, and is particularly concerned with improvements in beating engines of the continuously operating type.

6 The objects of my invention are,

First: To provide a beating engine of the type described having a capacity for producing the maximum quantity of pulp or stock per unit of time;

10 Second: To provide a beater of the type described comprising means for continuously and selectively withdrawing the finished pulp from the beating engine, and

15 Finally: To provide a beating engine of the character described which is simple in construction, easy to operate, reliable, and economical to manufacture.

20 Other objects of my invention will appear as this description progresses, reference being had to the accompanying drawings, in which—

Figure 1 is a plan of my improved beating engine;

25 Figure 2 is a longitudinal section therethrough, and

Figure 3 is a fragmentary view, partially in section, showing certain details of construction on an enlarged scale.

Throughout the several views, similar reference characters will be used for referring to similar parts.

Referring to the drawings, I have illustrated my invention as forming a part of a beating engine comprising the conventional tank 5 having the beating roll 6 mounted therein, and preferably provided with a back fall 7 of considerable height formed therein so as to insure comparatively rapid circulation of the contents of the tank.

40 The featherboard 8 of my improved beating engine may be of any desired construction, except as the end portions thereof are modified in a manner described later on. In the present case, I have illustrated the intermediate portions of the featherboard as comprising two spaced walls or partitions 9, which are held in spaced relation by suitable spacers 10. The end portions of the two end walls 9, which project beyond the spacers or partitions 10, are joined together at their lower portions by rounded walls 11, which form stuff boxes communicating with the discharge pipes 12 passing through the bottom of the beating engine.

For the purpose of removing the finished pulp or stock from the beating engine, I provide a plurality of vertically extending horizontally spaced rollers 13 which are journaled in suitable bearing strips 14 and 15, and which form continuations of the end portions of the walls 9. The bearing strips 14 and 15 are bent in the form of loops so that the rollers at each end of the featherboard form a chamber communicating with the stuff boxes for receiving the finished pulp from the beating engine.

It will be noticed from an inspection of Figure 1 that the chambers formed by the vertical rollers project into the rounded ends of the tank 5 past the centers of the radii of these rounded ends, so that the velocity of the contents of the tank is increased as it passes around the ends of the featherboard. I do this principally to prevent the coarser particles of unfinished stock from lodging in the spaces between the rollers, and also to cause rotation of the rollers, because such rotation tends to clear the rollers of strings and other similar foreign matter.

It will, of course, be understood that the lower ends of the rollers 13 extend below the water line of the beating engine, and that the pulp or stock, which has been reduced to a sufficient state of fineness, will pass out of the beating engine through the spaces between the rollers 13.

While I have discovered that rollers such as I have herein described are most satisfactory for the purpose for which they are used, it is to be clearly understood that these elements need not be rotated but may simply be rods spaced apart sufficiently to permit the finished pulp to be discharged from the beating engine.

It should also be understood that whereas I have disclosed a discharge chamber at each end of the featherboard, such construction is not necessary, a chamber at one end of the featherboard being sufficient for some purposes. Furthermore, it will be obvious that the rollers can be located in one of the external walls of the tank as well as in the central wall or partition 9.

While I have described the details of construction of the preferred embodiment of my invention, it is to be clearly understood that my invention is not limited to these de-

tails of construction, but is capable of other adaptations and modifications within the scope of the appended claims.

Having thus described my invention, 5 what I claim is:

1. The combination of a beating engine including a tank, a featherboard and a beating roll, of means for removing the finished pulp from said tank comprising a 10 plurality of vertical horizontally spaced rollers arranged to form a chamber at each end of said featherboard, and an outlet pipe connected with the lower end of each chamber.

15 2. The combination of a beating engine including a tank, a featherboard and a beating roll, of means for removing the finished pulp from said tank comprising a plurality of vertical horizontally spaced rollers arranged to form a chamber at one end of 20 said featherboard, and an outlet pipe connected with said chamber.

25 3. The combination of a beating engine including a tank, a featherboard and a beating roll, of means for removing the finished pulp from said tank comprising a plurality of vertical horizontally spaced rods arranged to form a chamber at one end of said featherboard, and an outlet pipe connected 30 with said chamber.

35 4. The combination of a beating engine including a tank, a featherboard and a beating roll, of means for removing the finished pulp from said tank comprising a plurality of vertical horizontally spaced rods arranged to form a chamber at one end of said featherboard.

40 5. The combination with a beating engine comprising a tank, a beating roll, and means for causing rapid circulation of the contents of said tank, of means for removing the finished pulp from said tank comprising a plurality of vertical horizontally spaced rollers arranged to form a chamber extending 45 below the water line of said tank, and an outlet pipe connected with said chamber.

50 6. The combination with a beating engine comprising a tank and a beating roll, of means for removing the finished pulp from said tank comprising a plurality of vertical horizontally spaced rods arranged to form a chamber extending below the water line of said tank, and an outlet pipe connected 55 with said chamber.

60 7. The combination with a beating engine comprising a tank and a beating roll, of means for removing the finished pulp from said tank comprising a plurality of spaced rods arranged to form the vertical walls of a chamber extending below the water line of said tank, and an outlet pipe connected with said chamber.

65 8. A beating engine comprising a tank, one wall of which comprises a plurality of

vertically spaced rollers extending below the water line.

9. A beating engine comprising a tank, one wall of which comprises a plurality of movable elements arranged to form a plurality of elongated slots lying below the water line. 70

10. A beating engine comprising a tank, one wall of which comprises a plurality of rotatable elements arranged to form a plurality of elongated slots lying below the water line. 75

11. A beating engine comprising a tank, a featherboard in said tank having a chamber formed therein, and means for continuously removing finished pulp from said tank and discharge it into said chamber. 80

12. A beating engine comprising a featherboard having a chamber therein for continuously receiving finished pulp formed by said engine, and means for conducting the finished pulp from said chamber. 85

13. A beating engine comprising a featherboard having a chamber therein for receiving the finished pulp formed by said engine, and means for continuously conducting the finished pulp away from said chamber. 90

14. In a beating engine, the combination of a tank, a mid-feather in said tank defining a closed path therein for the flow of pulp, a beating roll in said tank, and vertically pivoted rotatable discharge means at one end of said mid-feather and in continuation thereof for continuously discharging the pulp from said tank. 95

15. In a beating engine, the combination of a tank, baffle means in said tank defining a closed path therein for the flow of the pulp, a beating roll in said tank, and rotatable discharge means at one end of said baffle means and in continuation thereof for continuously discharging the pulp. 105

16. In a beating engine, the combination of a tank having baffle means defining a closed path therein for the flow of the pulp, a beating roll in said tank, and pulp discharge means defining a curved apertured surface at one end of said baffle means and around which the pulp passes in flowing around the end of said baffle means. 110

17. In a beating engine, the combination of a tank having a mid-feather therein defining a circuit for flow of the pulp, a beating roll in said tank, the pulp having an accelerated flow around one end of said mid-feather, and rotatable discharge means defining a substantially circular apertured surface at the latter end of said mid-feather through which the pulp is discharged, the rotatability of said discharge means tending to prevent fouling thereof by the pulp. 120

18. In a beating engine, the combination of a tank having a mid-feather therein defining a circuit for flow of the pulp, a beat- 125

ing roll in said tank, and a curved apertured surface at one end of said mid-feather defining the inner side of the path of flow of the pulp around the latter end of said mid-feather, said curved apertured surface discharging the pulp from said tank.

19. In a beating engine, the combination of a tank, a mid-feather in said tank defining a closed path therein for the flow of pulp, a beating roll in said tank, and means

rotatable on a vertical axis near one end of said mid-feather, said means by its rotation being adapted to facilitate the continuous discharge of finished pulp from said tank, and the passage of unfinished pulp along 15 said closed path.

In witness whereof, I hereunto subscribe my name this 20th day of October, 1922.

JAMES T. MURPHY.
